UNITED STATES PATENT OFFICE

ENOCH C. MOSES, OF DORCHESTER, MASSACHUSETTS.

PIANO-SOUNDING-BOARD PRESS.

No. 914,061.

Specification of Letters Patent.

Patented March 2, 1909.

Application filed October 13, 1908. Serial No. 457,633.

To all whom it may concern:

Be it known that I, ENOCH C. MOSES, a citizen of the United States of America, and a resident of Dorchester, in the State of Massachusetts, have invented a new and useful Improvement in Piano-Sounding-Board Presses, of which the following is a specification.

This invention relates to gluing presses for use in piano factories, and especially to the construction of a press for providing the sounding board with its customary oblique ribs.

The invention consists in certain novel combinations of parts, and each of such combinations, and in a piano sounding-board press embodying the same, all as hereinafter more particularly described.

The leading object of the invention is to adapt the vertically movable follower of the press, and therewith as many pressure-distributing springs as may be required, to be quickly and positively raised and lowered by two operatives at the respective ends of the press, without the aid of retracting springs, and with uniformity of pressure and direct control of the operation.

Another object is to provide for putting on the ribs of the sounding board all at one time, and with uniform tension and symmetry of arrangement.

Other objects will be set forth in the general description, which follows.

Two sheets of drawings accompany this specification as parts thereof.

Figure 1 is a top view of the improved press adapted for simultaneously gluing on the oblique ribs of a sounding board; Fig. 2 is a perspective view of a gage frame, shown in Fig. 1, for locating the ribs upon the sounding board within the press; Fig. 3 is a perspective view on a larger scale, of one of the pressure-distributing springs detached; Fig. 4 is a side elevation of the press represented by Fig. 1, with its follower elevated; Fig. 5 is a like view of the same press with the follower lowered, showing the gage frame, sounding board and ribs within the press; and Figs. 6 and 7 are fragmentary detail views showing one of the hand-lever eccentrics and the connections between the same and the follower on a larger scale; Fig. 6 being a section on the line A—B, Fig. 7.

Like reference characters refer to like parts in all the figures.

The improved press represented as a whole by Figs. 1, 4 and 5, has a strong bed frame, *a*, terminating at its top in a horizontal bed, *a'*, a superposed follower, *b*, of peculiar construction, two pairs of uprights, *c c'* and *d d'*, at the respective ends of the press, rigidly and securely attached to said bed frame *a*; two pairs of hand-lever eccentrics, *e e'* and *f f'*, pivoted between the upper ends of the several pairs of uprights; and stirrups, *g*, connecting each of said hand-lever eccentrics with a subjacent portion of the follower *b* guided by said uprights.

The follower *b* includes a pair of horizontal beams, 1 and 2, Fig. 1, parallel with each other and with the front and rear sides of the bed frame, having rabbeted ends which are guided by the several uprights *c c'* and *d d'*. Each of these beams is preferably and conveniently stiffened by means of a superposed truss, 3. A sufficient number of rigid bridge pieces, 4, corresponding in number and arrangement with the ribs of the pattern of sounding board for which the press is designed, are fixedly attached to the bottoms of the two beams, and a sufficient number of pressure-distributing springs, 5, are fixedly attached to the lower edges of said bridge pieces, which are preferably arranged edgewise, as shown in Figs. 4 and 5, to give them the required rigidity.

The pressure-distributing springs 5 are preferably of the construction represented by Fig. 3, each spring being composed of two thicknesses of suitable resilient metal, with their ends curved inward and then upward toward the top of the spring, as clearly shown in Fig. 3, and provided with screw holes, 6 and 7, Fig. 3, to facilitate their rigid attachment to the bridge pieces by wood-screws.

Each of the hand-lever eccentrics *e e'* and *f f'* may be described as a hand lever constructed with eccentric laterally projecting flanges, 8 and 9, Fig. 6, an eccentric periphery, 10, Fig. 7, and a concentric hub, 11, Fig. 7. Said eccentric flanges and periphery, in common, may be formed by a band of steel attached to the periphery of the body of the hand lever, as represented in Figs. 6 and 7. Each of said stirrups *g*, as shown in Figs. 6 and 7, embraces a subjacent end of one of said beams 1 and 2 within a groove, 12, Fig. 7, and interacts with the eccentric flanges, 8 and 9, of the superjacent hand

lever $e e' f$ or f' by a pair of inwardly bent terminal flanges or lips, 13 and 14, as best shown in Fig. 6.

The follower end may be, and preferably 5 is, provided with a bolster, 15, Figs. 6 and 7, of suitable material, to interact with the eccentric periphery 10 of the superjacent hand lever.

A pair of tie rods, $h h'$, Fig. 1, having 10 loops, 16 and 17, Figs. 4 and 5, at their respective extremities which embrace said concentric hubs 11 of the corresponding hand levers $e e'$ and $f f'$ at the respective ends of the press, complete the structure.

15 A sounding board is represented in Figs. 1 and 2 and Fig. 5 at i , and its ribs at 18.

The sounding board proper having been placed on the table a' of the press beneath the elevated follower b , Fig. 4, in proper condition, 20 its glued ribs are symmetrically arranged thereon with the aid of a rectangular gage frame, j , Figs. 2 and 5, which is constructed with internal notches, 19, Fig. 2, extending vertically from the top of the 25 frame to its bottom and fitted to the ends of the several ribs, so that when the ribs 18 respectively are dropped into said notches upon the sounding board they are located as desired and kept from displacement.

30 Stops 20 and 21, attached to the underside of the frame j to contact with the edge of the sounding board i on both sides of one of its corners, insure the location of the frame upon the sounding board so as to overlap 35 evenly on all sides, or as may be desired. When that operation is completed the several ribs 18 are directly beneath the bridge pieces 4 corresponding with the several ribs respectively. Two operatives then take 40 their places, face to face, at the respective ends of the press, and, each of them grasping a pair of the hand levers $e e'$ and $f f'$, the latter are pulled from the position represented in Fig. 4 to the position represented

45 in Fig. 5, compressing the pressure-distributing springs 5 beneath the follower b in contact with the several ribs 18 as in Fig. 5. In this operation the eccentric peripheries 10 of the hand levers interact with the 50 bolsters 15 of the follower b ; the trusses 3 and the tie rods h and h' prevent any yielding of the follower beams 1 and 2 and the uprights $c c'$ and $d d'$; and the pressure-distributing springs 5 equalize the pressure on 55 the ribs 18 at all points so as to insure their attachment with uniform tension, as aforesaid.

The sounding board i and frame j are left 60 in the press until the glue has set, and the operatives then release them by turning the hand levers $e e'$, f and f' from the position represented by Fig. 5 to the position represented by Fig. 4. In this operation the flanges 8 and 9 of each hand lever interact 65 with the lips 13 and 14 of the stirrups g , and

the latter interact with the grooved ends of the beams 1 and 2 of the follower b , so as to elevate the latter and free the springs 5 from the ribs 18. The sounding board i and frame j are then removed from the press and the frame is then separated from the sounding board and its ribs, leaving the product ready for use.

It will be obvious that presses for other sounding-board gluing operations may be 70 constructed on the same principles in part; known or improved substitutes for details of construction which are not essential to the respective combinations of parts herein-after claimed may be employed in the construction of the improved press; and other like modifications will suggest themselves to those skilled in the art.

Having thus described said improvement, I claim as my invention, and desire to patent 80 under this specification:

1. The combination, in a piano sounding-board gluing press, of a vertically movable follower including a trussed horizontal beam, a number of subjacent pressure-distributing 90 springs movable with said follower and arranged to contact with the work, a pair of uprights at each end of said beam, a hand lever pivoted between the upper ends of a pair of said uprights at each end of said beam 95 and constructed with a double-acting eccentric having laterally projecting eccentric flanges, an eccentric periphery and a concentric hub, means connecting said eccentrics with said beam, and a tie rod having loops at its extremities embracing said hubs of the eccentrics.

2. The combination, in a piano sounding board gluing press, of a vertically movable follower including a pair of horizontal beams 105 side by side and subjacent rigid bridge pieces connecting said beams, a number of subjacent pressure-distributing springs attached to said bridge pieces and arranged to contact with the work, uprights at the respective 110 ends of the press forming guides for the respective beams and supporting horizontal pivots above the beam ends, a pair of hand levers at each end of the press movable on said pivots and each constructed with a 115 double-acting eccentric having laterally projecting eccentric flanges and an eccentric periphery, and a stirrup interacting with said flanges of each eccentric and embracing the subjacent end of one of said beams.

3. A piano sounding-board gluing press having, in combination, a horizontal bed for supporting the work, a superposed vertically movable follower including a pair of horizontal beams side by side and subjacent 125 bridge pieces corresponding in number and arrangement with the ribs of the sounding-board, a number of subjacent pressure-distributing springs attached to said bridge pieces and arranged to contact with the 130

respective ribs of the sounding board, uprights at the respective ends of the press forming guides for both ends of each beam and supporting horizontal pivots above the 5 beam ends, a pair of hand levers at each end of the press movable on said pivots and each constructed with laterally projecting eccentric flanges and an eccentric periphery, and stirrups interacting with said flanges of the 10 several concentrics and embracing the subjacent ends of said beams, said ends of the beams being constructed and arranged to interact also with the peripheries of the respective superjacent eccentrics.

15 4. A piano sounding-board gluing press having, in combination, a horizontal bed for supporting the work, a superposed rectangular gage frame constructed with internal notches extending vertically through its top

and bottom and adapted to locate the ribs 20 individually upon the sounding board, a superposed vertically movable follower including horizontal beams side by side and subjacent bridge pieces corresponding in number and arrangement with the ribs of 25 the sounding board, subjacent pressure-distributing springs attached to each of said bridge pieces and arranged to contact with the several ribs of the sounding board, and means for depressing said follower to simultaneously and uniformly press the several 30 ribs into effective gluing contact with the sounding board, substantially as hereinbefore specified.
